UNITED STATES PATENT OFFICE.

XAVER PFRUNDER, OF WOHLEN, SWITZERLAND.

BRAIDING-MACHINE.

1,398,444.

Specification of Letters Patent. Patented Nov. 29, 1921.

Application filed June 3, 1921. Serial No. 474,803.

To all whom it may concern:

Be it known that I, XAVER PFRUNDER, a citizen of the Republic of Switzerland, residing at Wohlen, Switzerland, have invented certain new and useful Improvements in Braiding-Machines; and I do hereby declare the following to be a clear, full, and exact description of the invention, such as will enable others skilled in the art to which it appertains to make and use the same, reference being had to the accompanying drawings, and to letters or figures of reference marked thereon, which form a part of this specification.

This invention relates to improvements in braiding machines.

Braiding machines without guide plates are known in which the spool carrier is transferred from one driver to the adjacent driver through the agency of locking means adapted to move in a substantially vertical direction.

The locking means of such constructions are slidably arranged on a guide rod and are provided with a toothed part adapted to coöperate with a suitably shaped recess of the arbor of the spool carrier. Many disadvantages are, however, inherent to the above mentioned devices and the safe working is endangered in many ways, for instance: The sliding friction on the guide rod causes a considerable resistance to the movement of the locking means which resistance may further be increased, by oil and dust being deposited on the sliding faces and becoming resinous, to an extent that prevents an operation of the device. The point in which the pressure, caused by the locking means of one driver coöperating with the locking means of the next driver for the purpose of displacing the latter means, acts, is situated off the center line of the guide rod; therefore a comparatively great length of the sleeve gliding on the guide rod is required to prevent the edging of said sleeve and a great height of the lower part of the spool carrier results thereby.

The object of the present invention is to provide a device for effecting the transfer of the spool-carriers from one driver to another which overcomes the above mentioned disadvantages.

According to the invention each locking or switching means in the shape of a latch is so arranged at the lower part of the driver that its one end coacting with the

spool carrier performs a tilting motion around the other end resting on the driver when being brought in and out of engagement with the spool carrier. Further means are provided for preventing a turning motion of the spool-carrier during the switching operation and means for securing the spool-carrier in its upright position and for preventing any tilting of the carrier which might be caused by the centrifugal force.

Two constructional examples of the device according to the invention are shown on the accompanying drawings, in which:

Figure 1 is an elevation showing two adjacent drivers and the lower part of a spool-carrier in its position between the drivers;

Fig. 2 is a plan of Fig. 1, the right hand driver being shown in section along line II-II of Fig. 1;

Fig. 3 is an elevation corresponding to Fig. 1 of a modified construction;

Fig. 4 is a plan view of Fig. 3,

Figs. 5 to 7 are details of the lower parts of the spool carriers illustrated in Figs. 80 1 and 2 and 3 and 4;

Figs. 8 and 9 show the latch separately.

Fig. 10 illustrates a general arrangement of a braiding machine provided with the improvements according to the invention.

Referring first to the constructional example illustrated in Figs. 1 and 2, 1 denotes the base plate of the braiding machine, on which base plate tubes 2, acting as shafts for the drivers 3 are rigidly fixed. Each driver 3 is provided with a gear wheel 4, the wheels of adjacent drivers intermesh and cause adjacent drivers to rotate in opposite directions. To one or more of said gear wheels 4 rotation is imparted from a driving shaft in a known manner and the general arrangement of a braiding machine of this type is illustrated in Fig. 10 of the accompanying drawings. The upper portion 5 of the gear wheel body is of a substantially 100 cone shape. Above the gear wheel 4 a cylindrical disk 6 is provided which, together with an additional cylindrical disk 7 secures the spool carrier 8 in a vertical position.

To this end the spool carrier 8 is provided with two cylindrical flanges 9 and 10, between which the disk 7 of the driver 3 projects, the thickness of the disk 7 is slightly smaller than the vertical distance between the inner faces of the flanges 9 and 10, so that the weight of the spool carrier 8 is supported by the flange 10 resting on the top

face of the disk 7. The latter is provided at its circumference with semicircular notches 11 with which the part of the arbor of the spool carrier between the two flanges 5 is in engagement, whereby the spool carrier is caused to take part in the rotary movement of the drivers. In the construction illustrated four notches 11 are provided in every driver disk 7. The distance piece 12 10 situated between the disks 6 and 7 of the driver is provided with notches 13 to clear the lower flange 9 of the spool carrier.

The device for effecting the switching or the transfer of the spool carriers 8 from one 15 driver to the adjacent driver comprises the locking members or latches 14 arranged below the disk 6 of a driver in a radial direction to the latter. A latch is shown in detail in Figs. 8 and 9. Each latch consists 20 of a flat bar of rectangular cross-section, each end of said bar being shaped to form a hook. The inner hook 15 is in engagement with an annular groove 16 provided at the upper end of the conical part 5 of the driver. 25 The outer hook 17, the nose of which points upward, has V-shaped or beveled outer edges 18 and 19. With each latch a spiral spring 20 co-acts, the lower end of which resting in a cylindrical recess 21 provided 30 in the conical part 5 of the driver and the upper end of the spiral spring being recessed at 22 into the latch. The conical part 5 of the driver is further provided with lugs 23; between the two vertical sides 35 of each pair of lugs a latch is inserted. The distance between said vertical faces is greater than the width of the latch so that the latter can move freely in a vertical direction, but is guided laterally by said faces. 40 Each latch 14 is thus adapted to perform a tilting motion around the inner hook 15 as fulcrum and is, in its empty position, pressed against the lower face of the disk 6 of the driver 3 (in Fig. 1 the left hand 45 latch of the left hand driver 3 is illustrated in this position). It is to be noted that the lower face of the disk 6 of the left hand driver 3 in Fig. 1 is provided with key-way shaped recesses 24 into which the latches 50 14 are pressed in their empty position, whereas the disk of the adjacent drivers 3 are not provided with such recesses. By this means the latches 14 of adjacent drivers are arranged at different elevations so that 55 the outermost edges of the V-shaped parts of two latches are prevented from striking against each other when the latches are brought into engagement with each other upon the rotation of the drivers.

60 The lower end 25 of the arbor of the spool-carrier 8 is provided with a recess or notch 26 of a dove-tailed cross-section. The lateral walls of said notch are curved in the direction of said walls. The parts of the 65 cylindrical end of the arbor that are par-

allel to the notch are beveled or rounded off at 27. Insertion of the spool-carriers 8 into the drivers by hand at the beginning of the braiding operation or exchanging carriers during the operation is very much facilitated, inasmuch as the rounded off edge 27 glides on the face 19 of the V-shaped edge of the latch 14 and causes a displacement of the latter against the action of the spring 20 when a spool-carrier is pushed sidewise 70 upon the disk 7 of the driver. Toward the end of this sidewise movement of the spool-carrier on being inserted into the driver the tooth of the displaced latch is forced, by the action of the spring 20, to enter into the 75 notch 26 of the spool-carrier and to grip the latter. To provide for a reliable interlocking movement between the hook 17 of the latch and the notch 26 when the drivers are not exactly erect or when wear of the 80 moving parts has taken place, play is arranged between the two (Fig. 1). The latch is then somewhat inclined to the horizontal, *i. e.* it is in the position of the left hand latch of the right hand driver shown in 85 Fig. 1. The part 28 of the arbor of the spool-carrier 8 immediately below the lower flange 9 has the shape of a flat iron, the pointed part of which being arranged in the direction of the travel of the spool-carrier. This flat iron shaped part 28 prevents a turning of the spool-carrier in the 90 momentary position in which the switching from one driver to the other is carried out, when the latch of one driver has just been forced out of engagement with the notch and the latch of the next driver has not entered the notch 26. The turning motion is prevented by the lateral edges of the part 95 28 coming in contact with the edges of the 100 disks 6. On the lower face of part 28 and near its pointed end a rod 29 is provided extending vertically downward for the purpose of preventing a spool-carrier from being drawn out of engagement with the 105 drivers during the transferring movement, *i. e.* when the latches are both unlocked. The transfer of a spool-carrier is carried out in the following manner:

When a spool-carrier locked to one of the 115 drivers is carried around to the adjacent driver, the latch of the first driver, which is inclined to the horizontal direction as described above, comes into contact with the empty latch of the second driver, which 120 latch occupies a horizontal position. Thereby the V-shaped edge of the empty latch enters into the angle formed by the rounded off portion 27 and the beveled face 19 of the loaded latch, and the empty latch acts 125 in the manner of a wedge and causes a displacement of the other latch in a vertical direction whereby the loaded latch is lifted out of engagement with the notch 26, and the empty latch comes into engagement with 130

said notch. In Fig. 1 of the drawings the relative position of the latches is shown as they pass the plane going through the axes of the two drivers. The latch on the right hand driver is in its locking position and the latch of the left hand driver has just been displaced and is below the first mentioned latch.

The movement of the latches relative to the drivers during the locking and the unlocking are substantially tilting movements around the inner end of said latches and the locking and unlocking can be carried out irrespective of the direction in which the drivers rotate. The cylindrical recess 22 of the latch 14 into which the spiral spring 20 is inserted ends in a hole 30 of smaller diameter than the diameter of the recess (Figs. 8 and 9). Into this hole the shaft of a pin 31 is inserted when it is desired to bring a latch into its inoperative position, for instance, when the pattern of the braid has to be changed. The right hand latch of the right hand driver in Fig. 1 is shown displaced by a pin 31.

The constructional example shown in Figs. 3 and 4 shows some modifications to the means for holding the spool-carriers in an upright position and to the latch. The latter differs from the latch illustrated in Figs. 1, 2, 8 and 9 inasmuch as the inner tooth 15 is replaced by a pin 32. The pin 32 is suitably tapered and curved to allow of the tilting movement of the latch. For connecting the latch to the driver 3 holes 33 are provided in the conical part 5 of the latter, into which the pins 32 are inserted.

The means for holding the spool-carrier 8 in an upright position consist of the following parts:

Above the gear wheels 4 of the drivers, disks 34 are provided which contain the notches 11 into which the arbor of the spool-carrier is embedded in order to take part in the rotary movement of the driver. A cylindrical disk 35 is arranged on each driver at some distance from the notched disk 34; the disks 35 of adjacent drivers are arranged at different elevations. The diameters of said disks 35 are so chosen that disks of adjacent drivers overlap each other and project into slots 36, 37 provided in the enlarged portion 38 of the arbor of the spool-carrier. As the disks 35 enter the portion 38 from opposite sides the latter is of an S-shaped vertical cross-section. The extensive radial engagement of the slots 36, 37 and the disks 35 insures a correct upright position of the spool-carrier 8 and prevents a tilting of the latter. The edges of the disks 35 are rounded off in order to enable an easy entering of said disks into said slots. The extension of said disks 35 in the radial direction beyond the axis of the arbor effectively prevents a turning motion of the spool-carrier. The

notched disks 34 have their edges beveled in opposite directions. Thereby it is possible to arrange the disks 34 of adjacent drivers at approximately the same elevation. The overlapping of two adjacent disks 34 and 70 the thereby resulting extended notches 11 insure further a positive guidance of the spool-carriers during the transfer of the latter from one driver to the next. The operation of the latches during the transfer is the 75 same as described for the constructional example illustrated in Figs. 1 and 2.

The above described improvements in braiding machines according to the invention present the following advantages: 80

The power used for displacing the latches to cause the locking and unlocking movements is extremely small, lubrication of the moving parts is scarcely needed and a safe reliable working is obtained. The play provided between the tooth of the latch and the notch in the arbor of the spool-carrier insures a reliable working in case the drivers are not exactly mounted on the base plate and even after a considerable wear of the 90 members for effecting the transfer of the spool-carriers has occurred. The locking action of the tooth of the latch engaging with the dove-tailed notch is very effective at any speed of the machine and irrespective of the 95 direction of rotation of the drivers. The construction requires little space and the height of the drivers is kept very small whereby vibrations and the ruptures of the thread resulting therefrom are effectively prevented, 100 and the stability of the braiding machine and the life of the parts of the machine is materially increased.

I claim:

1. In a braiding machine, the combination 105 with a plurality of spool-carriers each having a recess, of drivers provided with notches for the reception of the spool-carriers, locking members each operatively connected at one end to a driver and at the other end adapted to engage in the recess of a carrier by performing a tilting motion on the end connected to the driver acting as a fulcrum, the locking member of one driver co-acting with the locking member of the adjacent driver irrespective of the direction of rotation of a driver, for performing said 110 tilting movement during the transfer of a carrier from one driver to the adjacent driver, and means for preventing a turning 115 motion of the carriers during the transfer of the latter from one driver to another.

2. In a braiding machine, the combination 120 with a plurality of spool-carriers each having a recess, of drivers provided with radially disposed notches for the reception of the spool-carriers, spring actuated elongated locking members having hooked ends, the inner end of each member being in operative 125 connection with the recess in a driver, the 130

outer end being adapted to engage with the recess of a carrier by performing a tilting motion on the inner end, the locking members of one driver co-acting with the locking members of the adjacent driver irrespective of the direction of rotation of a driver, for performing said tilting movement during the transfer of a carrier from one driver to the adjacent driver, and means for preventing a turning motion of the carriers during the transfer from one driver to another.

3. In a braiding machine, the combination with a plurality of spool-carriers, each having a recess in its lower end, of drivers provided with notches for the reception of the spool-carriers, radially disposed spring actuated elongated locking members provided with hooks at their inner ends, in operative connection with the recesses in the drivers, the outer ends being adapted to engage in the recesses of the carriers by performing a tilting movement on said inner ends, the locking member of one driver co-acting with the locking member of the adjacent driver irrespective of the direction of rotation of a driver, for performing said tilting movement during the transfer of a carrier from one driver to the adjacent driver, guide faces on said drivers for insuring the radial position of the locking members, and means for preventing a turning movement of the carriers during the transfer from one driver to another.

4. In a braiding machine, the combination with a plurality of spool-carriers each having a recess in the lower end of its arbor, of a plurality of drivers provided with notches for the reception of the spool-carriers and with beveled portions, radially disposed spring actuated elongated locking members provided with hooks at their ends, the inner hooks of said members being in operative connection with the recesses in the drivers, the outer hooks being adapted to engage in the recesses of the carriers by performing a tilting movement on the inner hooks, the locking member of one driver co-acting with the locking member of the adjacent driver irrespective of the direction of rotation of a driver for performing said tilting movement during the transfer of a carrier from one driver to an adjacent driver, guides on the beveled part of each driver for insuring the radial position of the locking members, a disk on each driver above its beveled portion, and a guide piece provided on the lower part of the arbor of each carrier adapted to be guided by the edges of the disks of adjacent drivers for preventing a turning motion of the carrier during its transfer from one driver to another.

5. In a braiding machine, the combination with a plurality of spool-carriers each having a recess at the lower end of its arbor, of a plurality of drivers each provided with notches for the reception of the spool-carriers and with a beveled portion, radially disposed spring actuated elongated locking members provided with hooks at their ends, the inner hooks being in operative connection with recesses in the drivers, the outer hooks being adapted to engage with the recess of each carrier by performing a tilting movement on the inner hooks, the locking member of one driver co-acting with the locking member of the adjacent driver irrespective of the direction of rotation of a driver for performing said tilting movement during the transfer of a carrier from one driver to the adjacent driver, guide faces arranged on the beveled part of the drivers insuring the radial position of the locking members, a cylindrical disk provided on each driver above its beveled portion, a guide piece provided on the lower part of the arbor of each carrier adapted to be guided by the edges of the cylindrical disks of adjacent drivers for preventing a turning movement of the carrier during its transfer from one driver to another, and a removable member adapted for insertion between a cylindrical disk and any desired locking member for holding the latter in its inoperative position.

6. In a braiding machine, the combination with a plurality of spool-carriers each provided with a recess, of drivers provided with notches for the reception of the spool-carriers, radially disposed spring actuated locking members having hooked ends, the inner hooks being in operative connection with recesses in the drivers, the outer hooks being adapted to engage with the recess of each carrier by performing a tilting movement on the inner hook, the locking member of one driver co-acting with the locking member of the adjacent driver irrespective of the direction of rotation of a driver for performing said tilting movement during the transfer of a carrier from one driver to the adjacent driver, each carrier having an enlarged portion on its arbor provided with horizontal slots arranged one above the other and opening toward opposite sides of the axis of the carrier and extending beyond said axis, and a disk provided on each driver at such elevation that the disk of one driver enters into one of said slots and the disk of the adjacent driver enters the other of said slots.

In testimony that I claim the foregoing as my invention, I have signed my name.
XAVER PFRUNDER.
